UNITED STATES PATENT OFFICE.

SAMUEL HERBERT LANYON, OF OAKLAND, CALIFORNIA.

JACK.

1,397,894.

Specification of Letters Patent.

Patented Nov. 22, 1921.

Application filed October 15, 1919. Serial No. 330,891.

To all whom it may concern:

Be it known that I, SAMUEL HERBERT LANYON, a subject of the King of Great Britain and Ireland, residing at Oakland, in the county of Alameda and State of California, have invented certain new and useful Improvements in Jacks, of which the following is a specification, reference being had therein to the accompanying drawings.

10 The invention relates to jacks and the object of the invention is to obtain a construction in which the operating mechanism is controlled solely by the movement of the handle lever independent of any projection 15 or cam, which is adjustable to control the raising or lowering of the lifting bar. Another object of the invention is to obtain a construction in which the moving pawl is movable over a range of several notches 20 in the lifting bar and its engagement with a notch is dependent upon the angular position of the lever. A further object of the invention is to obtain a construction in which the holding and moving pawls are automatically 25 yieldably disengaged from and engaged with the notches of the lifting bar. A still further object of the invention is to obtain a simple construction which does not require accurate machining of the parts of 30 the operating mechanism and will operate with the jack in any position. Still other objects of the invention reside in further advantages and in the novel arrangements and combinations of parts as more fully herein- 35 after set forth.

In the drawings:

Figure 1 is a front elevation of the jack embodying my invention;

40 Figs. 2, 3, 4 and 5 are side elevations of the jack showing the operating mechanism in different positions of adjustment;

Figs. 6 and 7 are cross-sections respectively on the lines 6—6 and 7—7 of Fig. 2;

45 Fig. 8 is a side elevation of the jack showing the arc of movement of the handle;

Fig. 9 is a cross section on the line 9—9 of Fig. 2.

50 A is the frame having the enlargement A' for housing the operating mechanism, and B the lifting bar having the notches B', B², B³, B⁴, B⁵, etc. The operating mechanism comprises the stationary cam C, the moving pawl E and the holding pawl G,

both of the pawls being engageable with the notches in the lifting bar. The stationary 55 cam C is secured at its opposite ends C' to the enlargement A'. The moving pawl E is pivotally mounted at one end E³ upon the handle lever F, which in turn is pivoted at F' upon the enlargement A', the opposite 60 end E⁴ of the moving pawl being engageable with the notches in the lifting bar. As shown, the end E³ of the moving pawl rests in a half-round groove in the handle lever F and the latter has check pieces F⁴ upon 65 opposite sides which are provided with alined apertures for receiving cylindrical projections E⁵ at opposite sides of the end E³. Pivotally mounted at E' near the opposite end E⁴ of the moving pawl is the rock- 70 bar D, there being a coil spring E² between the pawl and bar adapted to normally rotate the bar in a clock-wise direction. The holding pawl G is pivotally mounted at its lower end G' upon the enlargement A', its upper 75 end G⁵ being engageable with the notches in the lifting bar. The holding pawl is provided with the projection or extension G⁴ at its upper end in which is pivotally mounted at G² the rock-arm H, there being a coil spring G³ 80 between the holding pawl and the rock-arm adapted to normally rotate the rock-arm in a clock-wise direction to maintain its lower end H² bearing upon the abutment A² formed upon the enlargement A'. The rock- 85 bar D is provided with the cylinder head pins D' and D² at opposite ends adapted to respectively slide over the cam surfaces C² and C⁵ and engage the cam surfaces C⁴ and C³ upon the stationary cam C. The pin D' 90 is also adapted to engage the cam surface H' upon the rock-arm H.

The handle lever F has a suitable socket F² in its outer or free end for engagement with the handle J, which has the transverse pin J' through one end J² for engaging the notches F³ in the outer edge of the handle lever to permit revolving the end J² in the socket F² through an arc of approximately one hundred and eighty degrees. To raise 100 the lifting bar B the handle lever is swung through the arc X—Y and to lower the lifting bar the handle lever is swung through the arc X—Z, as more fully hereinafter described. These arcs are adjacent to each 105 other, so that in the manipulation of the

handle lever, the latter is swung through a considerable arc between its extreme limits of movement and in some cases would be impracticable to operate. To overcome this 5 objection the handle J has its end J², which engages the handle lever socket, inclined relative to the longitudinal axis of the handle, the angle of inclination being approximately one fourth of the total angle Y—Z. 10 In the raising operation the handle is engaged with the lever so that the outer end of the handle is at an angle below the horizontal or at the point Z' of the arc Y'—Z' and in swinging the lever through its arc X—Y. 15 the handle swings through the arc Z'—Y'. In the lowering operation the end J² of the handle is revolved in the socket F² approximately one hundred and eighty degrees to be engaged with the lever so that its outer 20 end is approximately at the point Y' and in the swinging of the lever through its arc X—Z the handle swings through the same arc Y'—Z' approximately. The outer end of the handle J is also adapted to be inserted 25 into the socket F² to permit of optional raising or lowering of the lifting bar without removing the handle from the socket.

In operation, to raise the lifting bar B, 30 the main lever F is moved through the arc X—Y and assuming both the holding and moving pawls to be respectively engaging the notches B⁵ and B², as shown in Fig. 2 in full lines, the first portion of upward 35 swinging of the handle lever F toward Y would move the moving pawl E downward and place the load of the lifting bar B upon the holding pawl G. The cylindrical head of the pin D' at the upper end of the rock 40 bar D rests against the cam surface C³ and the coil spring E² reacts upon the moving pawl E to swing the same about its pivot E³ in a counter clockwise direction to eject the moving pawl from its engaged notch B², 45 until the cylindrical head of the pin D' at the lower end of the rock-bar engages the cam surface C⁴. The end E⁴ of the moving pawl now clears the teeth formed by the notches in the lifting bar and the parts are 50 in the position, as shown in Fig. 3. Upon further raising of the handle lever F toward Y, the moving pawl with the rock-bar D moves downwardly and the head of the pin D' at the lower end of the rock-bar engages 55 the lower cam surface C⁴. The coil spring E² tending to swing the pin D' at the upper end of the rock-bar in a clockwise direction forces the cylindrical head of the same toward the cam surface C³ so that the upper 60 end E⁴ of the moving pawl is held against the contour of the teeth in the lifting bar, which will force the end E⁴ to engage with the notch B', as shown in Fig. 4. This notch is engaged slightly prior to or at the time 65 the handle lever reaches its upward limit of

travel at Y. Upon moving the handle lever F downward from Y toward X, the moving pawl E is moved upward and takes the load of the lifting bar. During this downward movement of the handle lever, the pivot 70 point E' of the rock-bar ascends parallel with the lifting bar B and soon after the commencement of the movement of the rock-bar D the head of the pin D' impinges against the cam surface C³ and rides thereon, 75 thereby moving the head of the pin D' upon the lower end of the rock-bar increasingly further away from the cam surface C⁴. During the downward movement of the handle lever, the holding pawl G moves over 80 the surface of the notch B⁵ and is yieldably forced into engagement with the notch B⁴. When the handle lever has reached its downward limit of travel at X the parts are in the position as shown in Fig. 2, with the 85 notch B' in the original position of B² and the notch B⁴ in the original position of B⁵.

To lower the lifting bar B, the handle lever is moved through its arc X—Z. The parts are assumed to be in the positions, as 90 shown in full lines in Fig. 2, with the holding pawl in engagement with the notch B⁵ and the moving pawl in engagement with the notch B². The handle lever F is first moved upward a very slight distance to place 95 the load of the lifting bar upon the holding pawl H when the spring E² reacts to eject the end E⁴ of the moving pawl E from the notch B² as previously described and shown in Fig. 3. The handle lever is then 100 moved downwardly, thereby raising the moving pawl E with the rock-bar D and forcing the head of the pin D' at the lower end of the rock-bar into engagement with the cam surface C⁵. The coil spring E² tends 105 to rotate the pin D' in a clockwise direction so that the head of the pin moves along the cam surface C², whereby the rock bar D moves bodily in a direction toward and approximately parallel with the notches in the 110 lifting bar and the end E⁴ of the moving pawl E engages the notch B³ in the lifting bar, as shown in Fig. 5. After the end E⁴ of the moving pawl has engaged 115 the notch B³, the end G⁵ of the holding pawl G is disengaged from its notch B⁶ by the following construction: The head of the pin D' at the upper end of the rock-bar D in its upward movement engages with the cam surface H' upon the rock-arm H to 120 rotate the same in a counter-clockwise direction, thereby removing the lower end H² of the rock-arm from engagement with the abutment surface A² upon the enlargement A'. The spring G³ is slightly compressed by 125 this movement and is now free to react upon the holding pawl G to rotate the same in a counter-clockwise direction to eject the end G⁵ thereof from engagement with the notch B⁵. The end G⁵ is ejected from the notch B⁵ 130

until the lower end H^2 of the rock arm engages the abutment surface A^2 , the parts being in the position, as shown in Fig. 5. The handle lever has now reached its lower limit 5 of travel at Z and upon return movement from Z toward X , the pivot point E' descends substantially parallel to the lifting bar B and the end G^5 of the holding pawl slides into engagement with the notch B^6 10 so that when the handle lever has reached its upper limit of travel near X , the parts are in the positions, as shown in full lines in Fig. 2, with the notch B^6 in the original position of B^5 and the notch B^3 in the original 15 position of B^2 .

From the above it will be readily seen that I have obtained a simple construction in which accurate machining of the parts is not required and, furthermore, the operation is 20 controlled solely by the movement of the handle independent of any manually-controlled levers. Furthermore, the holding and moving pawls are yieldably disengaged from and engaged with the notches of the 25 lifting bar at proper times dependent upon the position of the moving pawl and consequently of the handle lever.

What I claim as my invention, is:

1. In a jack, the combination with a 30 notched lifting bar, of holding and moving pawls, engageable with the notches in said bar, springs normally forcing said pawls into engagement with the notches, and means dependent upon the position of said moving pawl for reversing the action of said springs to eject said pawls out of engagement with the notches.

2. In a jack, the combination with a notched lifting bar, of holding and moving 40 pawls, engageable with the notches in said bar, springs independent of each other for normally forcing said pawls into engagement with the notches, and means dependent upon the position of said moving pawl for 45 automatically reversing the action of said springs to withdraw said pawls out of engagement with the notches.

3. In a jack mechanism, the combination with a standard and a notched lifting bar 50 slidably engaging said standard, of a holding pawl pivoted upon said standard and adapted to engage the notches of said bar, a lever pivoted upon said standard, a moving pawl engageable with the notches of said bar and 55 pivoted upon said lever, and independent yieldable means controlling the engagement of said pawls with said notches and controlled by said moving pawl.

4. In a jack, the combination with a 60 notched lifting bar, of a moving pawl engageable with the notches in said lifting bar, a rock bar pivoted upon said pawl, a spring tending to relatively rotate said rock bar and pawl, a cam, means at opposite ends 65 of said rock bar engageable with said cam,

means for moving said pawl with its rock bar to force said means of opposite ends of said rock bar separately into contact with said cam for respectively engaging and disengaging said pawl with and from the 70 notches.

5. In a jack, the combination with a notched lifting bar, of a pawl engageable with the notches in said lifting bar, a rock member carried by said pawl, a spring between said pawl and rock member for normally rotating said pawl relative to said rock member to engage one of the notches when one end of said rock member is fulcrumed, and means for fulcruming the opposite end of said rock member and removing said one end from its fulcrum whereby said spring will rotate said pawl relative to said rock member to disengage from its notch. 85

6. In a jack, the combination with a notched lifting bar, of holding and moving pawls adapted to engage the notches in said bar, a lever for operating said pawls, and yieldable means for automatically engaging 90 said pawls with the notches in said lifting bar, said means controlled solely by the rotatable position of said lever.

7. In a jack, the combination with a notched lifting bar, of pawls engageable 95 with the notches in said lifting bar, rock members pivotally mounted upon said pawls, springs between the respective pawls and rock members tending to relatively rotate said rock members and pawls, a cam, means 100 for moving one of said pawls with its rock member to force one end of said rock member into contact with said cam for engaging said pawl with one of the notches in said lifting bar, said rock member upon said 105 moved pawl adapted to contact with said rock member upon said other pawl to release said other pawl from its notch in the lifting bar.

8. In a jack, the combination with a lifting bar, of a lever movable through different arcs for respectively raising and lowering said lifting bar, and a handle engageable with said lever for moving the same through said different arcs, the free end of said handle movable through substantially the same arc. 110

9. In a jack, the combination with a standard, of a notched lifting bar slidably engageable therewith, a lever pivoted in said 120 standard, movable through adjacent arcs for raising and lowering said lifting bar, a pawl upon said lever and engageable with the notches in said lifting bar, and yieldable means carried by said pawl for controlling 125 the position of said pawl when engaging said notched lifting bar, said yieldable means being dependent upon the angular position of said lever.

10. In a jack the combination with a 130

standard, of a notched lifting bar slidably engageable therewith, a lever pivoted in said standard, movable through adjacent arcs for raising and lowering said lifting bar, a pawl upon said lever and engageable with the notches in said lifting bar, yieldable means carried by said pawl for ejecting

and withholding it from engagement with said lifting bar when said lever is at the common point between the raising and lowering arcs.

In testimony whereof I affix my signature.

SAMUEL HERBERT LANYON.
